UNITED STATES PATENT OFFICE.

WARREN E. BEADLE, OF WISCONSIN RAPIDS, WISCONSIN, ASSIGNOR TO BELOIT IRON WORKS, A CORPORATION OF WISCONSIN.

FAN FOR PAPER DRIERS.

Application filed May 19, 1924. Serial No. 714,229.

To all whom it may concern:

Be it known that I, WARREN E. BEADLE, a citizen of the United States, and a resident of the city of Wisconsin Rapids, in the county of Wood and State of Wisconsin, have invented certain new and useful Improvements in Fans for Paper Driers; and I do hereby declare that the following is a full, clear, and exact description of the same, reference being had to the accompanying drawings, and to the numerals of reference marked thereon, which form a part of this specification.

In paper making machines the heavy saturated air in the driers is more or less dead and acts to retard the drying of the paper. There have been various schemes tried out for the purpose of producing a circulation through the paper machine drying cylinders to remove the heavy saturated air, but not any of said schemes has proven entirely satisfactory.

This invention relates to a simple and inexpensive arrangement wherein the circulation through the drying cylinders of a paper making machine is improved by the addition of fans used on the driving gears of the drying cylinders and by the addition of a hood or baffle positioned over the paper machine within the machine room.

It is an object of this invention to provide an improved circulation of the saturated air between the drying cylinders of a paper making machine by providing the drying cylinder gears with fan blades.

It is also an object of this invention to provide a method of withdrawing moisture laden vapors from between paper machine dryers by equipping the drying cylinder gears with ventilators for drawing hot air from beneath a hood, between the cylinders and out of the machine room with the aid of an exhaust fan.

It is an important object of the invention to provide a simple improved inexpensive arrangement for withdrawing saturated air from between the drying cylinders of a paper making machine by providing ventilators operable from the machine to withdraw the saturated air and permit the circulation of hot air or dry air through the machine room and between the drying cylinders.

Other and further important objects of this invention will be apparent from the

disclosures in the specification and the accompanying drawings.

The invention (in a preferred form) is illustrated in the drawings and hereinafter more fully described.

On the drawings:

Figure 1 is a transverse vertical section through a machine room and illustrating the circulation of air through the drying machines by means of arrows.

Figure 2 is a fragmentary side elevation of a portion of the Fourdrinier unit of a paper making machine showing the cylinder driving gears equipped with fan blades.

Figure 3 is a fragmentary top plan view of the portion of the machine illustrated in Figure 2 and showing one of the gears in section.

As shown on the drawings:

The reference numeral 1 indicates a machine room having a cupola or tower 2 on the roof thereof in which an exhaust fan 3 is mounted. A hood or baffle 4 is supported within the machine room above the drying sections of two paper making machines positioned side by side. Hot air supply pipes 5 are supported within the machine room 1 and are connected with any suitable source of supply.

Inlet pipes 6 project from the supply pipes 5 into openings in the sides of the hood 4 above the tops of the paper making machines. Each of the paper making machines briefly comprises a framework 7 having a plurality of drying cylinders 8 provided with trunnions 9 and 10, which are journaled in bearings on the machine frame. Driving gears 11 are supported on the trunnions 10 and are connected to be driven from any suitable source of power to cause rotation of the drying cylinders.

Integrally formed or rigidly secured on alternate spokes of each of the gears 11 are fan blades 12. While the fan blades are illustrated and described as being mounted on alternate spokes of the gears, it will of course be understood that any number of fan blades may be provided and mounted in any desired position on the gears 11 to cause the necessary circulation of saturated air between the drying cylinders 8.

The hood 4 and the two paper making machines divide the interior of the machine room into a hot or dry air receiving cham-

ber 13 below the hood and between the two machines, side chambers 14, and an upper outlet chamber 15 above the hood 4. The outlet chamber 15 communicates with the 5 cupola chamber within which the exhaust fan 3 is mounted.

- When the paper making machines are operating hot air or dry air is supplied from the supply pipes 5 and the auxiliary pipes 10 6 to the chamber 13. Due to the action of the fan blades on the rotating gears 11, the hot air is drawn between the cylinders 8 of each machine and is directed as indicated by the arrows from the chamber 13 outwardly 15 to the two side chambers 14 and then upwardly into the upper chamber 15. The action of the exhaust fan 3 in the cupola serves to exhaust the heavy saturated air from the machine room. 20 The fan blades on the gears 11 thus afford a simple and inexpensive means whereby the heavy saturated air, resulting from the drying of paper, is drawn from between the drying cylinders and exhausted, thereby permitting 25 a constant supply of hot or dry air to be circulated in the machine room.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

- 35 1. The combination with paper making machine drying cylinders and the driving gears thereof, of means carried by the gears to create a circulation of air between said cylinders.
- 40 2. In a paper making machine the combination with the drying cylinders thereof, of means for driving the same and also causing a circulation of air between said cylinders.
3. The combination with a machine room 45 and paper making machines therein, of drying cylinders forming a part of said machines, gears for driving said cylinders, and members mounted on said gears for causing a circulation of air through the machine room and between said cylinders.
- 50 4. The combination with a machine room

and paper making machines therein, of drying cylinders forming a part of said machines, gears for driving said cylinders, a hood in said room above the machines, means 55 for supplying hot air into the room below said hood, and fan blades mounted on said gears to cause a circulation of the hot air between said cylinders and through the machine room.

5. The combination with a machine room, of paper making machines therein, an exhaust fan in the roof of said machine room, a hood mounted in the machine room above the machines, drying cylinders forming a 65 part of the paper making machines, gears for driving the cylinders, hot air pipes for supplying the machine room with hot air, and fan blades carried by said gears to cause a circulation of the hot air between said cylinders and over said hood with the aid of the exhaust fan.

6. In a drier section of a paper making machine, means for removing the vapors generated therein consisting of fan elements fastened to each of the drier rolls and being of such size as to occupy one entire side of the machine, thus adapted to move a column of air uniformly through said machine.

7. In a paper making machine, rolls journaled transversely of the machine, driving gears fixed to the shafts of said rolls, and fan elements carried by said gears adapted to exhaust the air between said rolls.

8. In a paper making machine, an apertured frame in each side of the machine, rolls journaled transversely of the machine between said frames, driving gears fixed to the shafts of said rolls, and fan elements carried by said gears adapted to exhaust the 90 air between said rolls.

9. In a paper making machine, rolls journaled transversely of the machine, driving gears fixed to the shafts of said rolls, a hood over said rolls, and fan elements occupying 95 substantially the entire space at one side of said machine and below said hood, thus adapted to remove the entire column of air thereunder past said rolls.

In testimony whereof I have hereunto subscribed my name.

WARREN E. BEADLE.
